assignors to Mrs. Jean Ratajack, Chicago, Ill.

Application March 15, 1946, Serial No. 127,525

Term of patent 14 years

(Cl. D9—2)

To all whom it may concern:

Be it known that we, Ted R. Stacey and Roy H. Lesner, citizens of the United States, residing at Chicago, in the county of Cook and State of Illinois, have invented a new, original, and ornamental Design for Combined Folding Toothbrush and Container Therefor, of which the following is a specification, reference being had to the accompanying drawing forming a part thereof, in which:

Fig. 1 is a view in perspective of a combined folding toothbrush and container therefor with the container and toothbrush in assembled position, embodying my new design;

Fig. 2 is a perspective view thereof showing the toothbrush in partially raised position; and

Fig. 3 is a perspective view thereof showing the container and toothbrush in disassembled position.

We claim:

The ornamental design for a combined folding toothbrush and container therefor, substantially as shown.

TED R. STACEY.
ROY H. LESNER.
